(57) CLAIM

The ornamental design for a label, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a label, showing our new design.

The “BIBICONE” and “SHARE KOREAN FLAVOR” trademark materials forming part of the claimed design are registered trademarks of CJ CHEILJEDANG CORPORATION.
